(57) **CLAIM**

The ornamental design for an electronic device with graphical user interface, as shown and described.

DESCRIPTION

FIG. 1 is a front view of an electronic device with graphical user interface showing the claimed design; and,

FIG. 2 is a front view of another embodiment of an electronic device with graphical user interface showing the claimed design.

The outer broken lines in the figures show an electronic device having a display screen, and form no part of the claimed design. The other broken lines in the figures show portions of the graphical user interface that form no part of the claimed design.

The figures are illustrated to show contrasting appearance. Areas of the electronic device with graphical user interface that appear in different shades of gray represent areas with contrasting appearances.
